FLUORESCENT SCREEN

Friedrich Ring, Berlin-Tempelhof, and Georg Weiss, Berlin-Dahlem, Germany

Application December 15, 1937, Serial No. 180,010
In Germany October 26, 1936

2 Claims. (Cl. 250—150)

The invention relates to fluorescent screens and to cathode ray tubes containing such screens. It is particularly concerned with screens for making visible pictures or drawings of any kind, for instance lines, diagrams and letters. The arrangement according to the invention is especially adapted to produce bright television images with changing contents, advertising pictures in black and white only or oscilloscopes.

10 Among the objects of the invention are: to produce a fluorescent screen emitting light under the impact of electrons and in which the emission of light continues at a uniform rate until it is stopped by a reverse controlling force; to provide a screen structure having light emitting and dark portions adjacent to one another on the same surface, the whole surface of the screen being bombarded by electrons of the same source; to provide a self-controlling fluorescent screen 20 having definite areas of two different potentials; to provide a cathode ray tube including a fluorescent screen with a material emitting secondary electrons under the impact of primary electrons and a cathode emitting electrons at a uniform rate over the whole area of the screen; to provide a screen structure on which a fluorescent image is stored by electrical charge storage during the longer part of the period between successive pictures and cancelled out shortly before 30 a new picture is stored.

Further objects are to provide a method of making a self-controlling screen and of making a screen structure from which the pictures are easily obliterated in quick succession.

35 Other objects of our invention will be apparent as will be specifically pointed out in the description forming a part of the specification but we do not limit ourselves to the embodiments of the invention herein described as various forms may be adopted within the scope of the claims.

40 Referring to the drawing:

Fig. 1 is a sectional view of a cathode ray according to the invention.

45 Figs. 2 and 3 are diagrams explaining the operation of the tube represented in Fig. 1.

Fig. 4 is a cross section through a screen structure according to the invention on an enlarged scale and

50 Fig. 5 is a plan view of a part of the screen structure of Fig. 4.

The tube of Fig. 1 contains within an envelope 1 a screen 2 of insulating material with a layer 3 of fluorescent material. A grid electrode 4 is arranged in front of the screen and connected by a lead 5 to the outside. The tube contains

furthermore a cathode 6 having for instance the form of a wire spiral bent to form a ring and connected by conductors 7 and 8 to a heating battery 9. The tube contains furthermore a cathode 10 of conventional type for producing a cathode ray and connected to a battery 11. A control electrode 12 is arranged in front of the cathode 10. This electrode has the form of the well-known Wehnelt cylinder. Externally of the tube a concentrating coil 13 is situated around the 10 neck of the tube. Two deflecting systems 14 and 15 are indicated schematically and constructed in accordance with the usual practice of oscilloscopes and television tubes.

In the operation of the device a potential of 15 +500 V. is applied to grid 4 with respect to the potential of cathode 6 as zero-potential. Cathode 10 has a potential of -1000 V. against cathode 6. In order to obtain a stationary record on the screen the cathode ray emitted by cathode 10, modulated by electrode 12 and concentrated by coil 13 is deflected over the screen 2 so that a local potential distribution is produced and stored on the screen in such a manner that certain portions of the screen have a potential 20 lying above a value of for instance 250 V. against cathode 6 and the remaining portions have a potential below 250 V. The potential of 250 V. corresponds to the critical potential at which 25 electrons hitting the screen liberate the same 30 number of secondary electrons as primary electrons are arriving on the screen. It is assumed that the distribution of potential is maintained approximately constant for a period of time owing to the insulating qualities of the screen 2 35 and the fluorescent layer 3.

If now the source of electrons 6 is energized the whole screen is sprayed diffusely and uniformly with electrons. These electrons are accelerated to a velocity of 500 V. by the grid 4 40 but they reach the fluorescent layer with a velocity depending upon the potential of the respective surface element of the screen. An element having a potential above 250 V. is bombarded by electrons of high velocity and more 45 secondary electrons are liberated than primary electrons reach this element. The potential of the element is made more positive by the loss of electrons and this increase of potential is continued until the potential of grid 4 is reached. 50 This is the end value which cannot be surpassed.

Another element of the screen having a potential lower than 250 V. is reached by electrons having a comparatively low velocity and the number of secondary electrons is smaller than the 55

number of primary electrons reaching this element. The potential of the element is therefore decreased towards zero-potential. The screen contains therefore during the operation areas having zero-potential and remaining dark because no electrons from source 6 can reach these areas and other areas with a potential of 500 V. emitting a continuous light.

Fig. 2 shows graphically the two stable conditions under which the screen is working. The 10 ordinate 1 gives the ratio of the number of secondary electrons to the number of primary electrons

$$15 \quad \frac{s}{p}$$

the abscissa indicates the velocity of the impacting electrons in volts. Fluorescent materials as ordinarily used in cathode ray tubes for instance zinc sulfide have a characteristic curve "a" reaching the value of

$$20 \quad \frac{s}{p} = 1$$

25 at 250 V. All elements of the screen having a potential below this critical value, show a decrease in potential under the influence of the electrons emitted by cathode 6 as indicated by arrow 16 and all elements having a potential above this value are finally reaching a potential 30 of 500 V. as indicated by arrow 17. The same holds true when the device is operated with a potential lying on the descending part of the characteristic curve in Fig. 2. The critical potential is then according to this curve 2700 V. 35 and the positive end potential is defined by the potential of grid 4.

40 In order to remove the image stored and appearing on screen 2 it is possible to bombard the whole screen by the concentrated ray from source 45 10 so that all parts of the screen take on the high potential and are luminating brightly. In order to control the screen in the reverse direction and to make it dark it is possible to lower the potential of grid 4 for a short period of time so that 45 all parts of the screen assume a potential below the critical value.

50 The critical value of 250 V. depends upon the material of the fluorescent layer and its treatment and can be changed in fairly wide limits by the correct selection of the material. It is also possible to change the potential on grid 4 and cathode 10 in wide limits. Experiments have shown, that it is possible to maintain luminating and dark portions on the screen adjacent to one 55 another also in case the base of the screen consists of a metal plate. The insulating properties of the fluorescent material are sufficiently good to build up local charges on the screen.

60 In order to obtain a stationary image remaining unchanged it is necessary to maintain the following operating conditions explained in connection with Fig. 3. The fluorescent material 19 is arranged upon the insulating support 8 and bombarded by electrons in the direction of arrows 20. It is assumed that the fluorescent material has the potential 0 on the right hand side of the figure as far as it is represented black and has a potential of 500 V. in the left hand part. The distribution of the potential is indicated by curve 21 showing the potential in dependence from the local extension of the screen. A large difference of potentials exists at the place of arrow 22 and the slope of the local difference in potential depends upon the conductivity of 75 the material. Experiments have shown that the

lines separating areas of high potential from those of low potential, i. e. separating the bright and dark parts of the screen are subject to a displacement depending upon the velocity of the electrons emitted by cathode 6. In case the electrons arrive too slowly the dark portions are increasing and in case the velocity of the electrons is too high the bright portions of the screen are increasing. This displacement would destroy the picture after a certain time and care must be taken to stabilise the picture. The direction and rate of the displacement depend also from the material of the screen and the support of the screen.

10 According to the invention the velocity of the 15 diffusely emitted electrons is exactly adjusted in such a manner that neither a displacement in one or the other direction occurs. In the above mentioned example of zinc sulfide as screen material a voltage of about 500 V. has been found 20 as critical for a stationary picture. It can be assumed that the critical value of the material of

$$25 \quad \frac{s}{p} = 1$$

corresponds to about half this voltage, i. e. to 250 V.

30 In case the screen is used for producing moving pictures for instance for cinematographic or television purposes it is necessary to produce the picture and to remove it within a short period of time of for instance $\frac{1}{25}$ of a sec. It is preferable to extinguish or cancel the picture not momentarily over the whole screen surface but only on that part of the screen on which the new picture is produced immediately thereafter 35 in order to obtain pictures of uniform brightness which are free from flicker and as bright as possible. A second concentrated cathode ray 40 may be used for cancelling the pictures; this ray is deflected in a similar manner as the recording pencil but is displaced a few lines in advance of the recording pencil. It is also advantageous to divide the screen and/or the grid 45 in front of the screen into a number of sections parallel to the lines of the picture. The cancellation is effected in one section only of the screen at a time shortly before the recording cathode ray is touching this part of the screen.

50 A particularly simple embodiment is represented in Figs. 4 and 5. Fig. 4 shows the screen of a tube similar to that of Fig. 1 with two cathodes. The screen is represented on an enlarged scale and consists of a number of parallel wires 23 insulated from one another. The wires are partly embedded in the insulating material 24 and are covered with fluorescent material 25. The fluorescent material is covering also the exposed surface of the insulating material 24. Fig. 5 shows a view of the screen from the side of the cathode. The wires 23 are bent upwardly on the right hand side and are terminating in or upon the insulating material forming the carrier of the screen. A conductor 24 is arranged at the edge of the screen. A conductor 24 is arranged at the edge of the screen. The strip of material 25 between the conductor 24 and the ends of wires 23 is semi-conducting so that all the wires 23 are connected by way of this resistance with a source of potential of 500 V. The surface of the wires is carefully cleaned between the dotted lines 26 and 27 and a strip of finely divided carbon, for instance graphite, is applied. Furthermore each pair of adjacent wires is connected by conducting bridges 28. 75

These portions 28 have a surface or a coating of material easily emitting secondary electrons. The number of wires corresponds at least to the number of lines of the television transmission but is preferably larger.

The operation of the device is as follows: The cathode ray modulated by the control electrode 12 is deflected in the direction of arrow 29 over the surface of the screen while at the same time the whole screen is diffusely bombarded with electrons of lower velocity. At the end of the movement the ray impinges upon the non-emitting strip 26, 27. The wires crossed over by the cathode ray at this place receive more electrons than they give off so that the potential of these wires is sharply lowered. As the strip of graphite is somewhat conducting also two or three adjacent wires will attain a more negative potential. It is preferable to control the ray during this time for highest intensity and the deflecting field is controlled preferably in such a manner that the ray is remaining for a while upon the strip 26, 27. It may be preferable also to make the strip broader than represented in the drawing. The quick decrease of potential of the wires serves to cancel the illumination in that part of the screen lying near the wires. The screen is therefore brought to darkness a few lines in advance of the cathode ray. The cathode ray is then quickly returned and writes the second line as indicated by arrow 30. During the return movement it touches the sections 28 of wires which are more closely adjacent to its next path, so that these wires are made more positive thereby. During the whole time of recording, the wires brought quickly to a lower potential are slowly made more positive by the current flowing through the semiconductor 25, so that the wires assume again the function of grid 4 of Fig. 1, the illumination near these wires being however cancelled. Only when the modulated cathode ray is charging definite parts of the line to a more positive potential the illumination starts at these points and will remain under the influence of the electrons emitted by cathodes 6 until the concentrated ray is touching again the upwardly bent edges of the wires between lines 26 and 27.

A screen of this type may contain separate cancelling and accelerating electrodes. It is also possible to divide the fluorescent material into single insulated elements by cutting lines into the layer or by spraying the fluorescent material through a grid which is removed afterwards. Such a screen consisting of insulated fluorescent particles has the advantage that the displacement effect described in connection with Fig. 3 is minimised.

As the elements of the screen are illuminating either brightly or not at all the pictures are only

black and white without half-tones. It is however possible to obtain half-tone-pictures by changing the width of the illuminating lines. The modulated ray 10 is therefore controlled in such a manner that chiefly the diameter or size of the spot is changed while the intensity of the ray per surface unity is kept approximately constant. The visibility of the lines can be decreased by using an interlaced scanning method.

It is preferable to use as high a potential as possible between the cathode 6 and the screen. This however is only possible in case the factor

$$\frac{s}{p} = 1$$

is reached for a very high velocity of primary electrons. According to the invention a material is used for the screen in which the value

$$\frac{s}{p} = 1$$

is reached above 500 V. or more.

The effect of the cancelling strip 26, 27 may be increased by multiplying the effect of decreasing the potential by a multistage secondary emission multiplier for instance of the grid type.

The potential distribution maintained on the screen can also be used for controlling other effects. It is also within the scope of the invention to produce an electron optical image of the screen surface upon another surface and to separate locally the production of the potential distribution and the luminous effect.

We claim:

1. In a cathode ray tube an insulating plate, a fluorescent screen on said plate, a source of electrons for uniformly bombarding the whole area of said screen with electrons, an accelerating electrode in front of said screen having a fixed potential above the critical value at which the number of secondary electrons emitted by the screen exceeds the number of primary electrons, means for charging elemental areas of said screen to different potentials, and means for intermittently bringing the accelerating electrode to negative potential.

2. In a cathode ray tube a plate, fluorescent insulated elemental areas on said plate, a source of electrons for uniformly bombarding the whole area of said plate with electrons, an accelerating electrode having a fixed potential of twice the critical value at which the number of secondary electrons emitted by the plate exceeds the number of primary electrons, and means for charging elemental areas of said plate to different potentials.

FRIEDRICH RING.
GEORG WEISS.
